ABSTRACT: An input typewriter-output printer system where characters originate from either a keyboard or computer and are encoded to binary form to be recognized by an AND gate circuit. The outputs of the AND gates are fed to a matrix generator that activates high-voltage gates to form characters. Each character is parallel fed along a fixed line that is in alignment with electro-sensitive paper upon which the characters are printed by arcing through to a conducting platen divided into segments by insulators, each segment corresponding to one of the parallel characters on the fixed line. A binary up-down counter controlling the voltage to the segments sequentially completes the arcing circuit of the parallel characters through the paper.

ELECTRO-ARC PRINTING SYSTEM

BACKGROUND OF THE INVENTION

This invention relates to an electroarc printing system and more particularly to a combination input typewriter-computer readout printer.

Presently most computers, data processors and communication (digital data) systems must utilize two devices to perform the data in/out functions of each system. These devices usually consist of a typewriter for data insertion to the system and a low or high-speed printer which performs the data print out function for the system. Two devices are necessary for the data in/data out function because the machine that performs the data in functions has the disadvantage of being mechanically actuated in some fashion. The mechanical operations are time consuming and thereby do not have the capability for high-speed printing as demanded to accomplish the data out function.

The gated line matrix electroarc printing process of the present invention permits the design of a flexible typewriter-printer combination device which will perform both the data in/out system functions. The electronic typewriter-printer combination device is capable of accepting and performing the low and high-speed data-printing functions on demand from an operator of a machine data buffer or computer. Being primarily electronic in operation, mechanical movements are minimized with an attendant large increase in reliability and ease of maintenance.

SUMMARY OF THE INVENTION

The gated line matrix electroarc printing process permits both low and high printing speeds by electronically gating high voltage (arcing) pulses through electrosensitive paper using a fixed line wire array that has multiple characters. The electronic gating circuitry sequentially gates each character for printing and is capable of countdown (backspacing) when the printing character is an error. The binary-coded character arrives at the character-printing circuit in parallel binary form and triggers (SETS) appropriate bistable multivibrators. The SET and RESET outputs of the multivibrators are applied as inputs to character recognition AND gates. Each binary-coded character received activates one of the AND gates. The activated AND gate provides a signal to a dot matrix generator that determines the character geometry of dots to be printed. The output of the dot matrix generator which represents the required dots to be printed triggers dot print gates which provide high voltage isolation for the dot matrix generator and provide a high voltage grounding path for the print pulse.

A timing pulse is received each time a binary coded character is generated which steps a Gray (up-down) counter. The output of the counter is applied to count recognition AND gates. Each count in the counter activates one of the recognition gates which triggers the appropriate high voltage print pulse gate. The output of the high voltage gate is applied to a character platen which provides a print pulse arcing path through electrosensitive paper to the fixed line matrix array and characters are serially printed on the line. The physical location of the character to be printed is determined by the count in the Gray counter.

It is therefore an object of the invention to provide a novel electroarc printing system.

It is another object to provide an electroarc printing system that prints at both high and low printing speeds.

It is still another object to provide a combination typewriter for data insertion into a computer system and a readout printer.

It is still another object to provide an electroarc printing system that is capable of backspacing to correct errors. It is still another object to provide an electroarc printing system having a fixed printing head and using electronic steering where only the paper moves, thereby eliminating the costly mechanical movement of a moving printing head.

These and other advantages, features and objects of the invention will become more apparent from the following description taken in connection with the illustrative embodiment in the accompanying drawings, wherein: DESCRIPTION 5 OF THE DRAWINGS

FIG. 1 is a block diagram showing the general system which embraces the invention;

FIG. 2 is a block diagram showing the character printing circuit; and

FIGS. 3a and 3b are expanded block diagrams of that shown in FIG. 2. DESCRIPTION OF THE PREFERRED EMBODIMENT

As shown in FIG. 1, keyboard 11 performs a character generation function and provides data and synchronizing signals to system 13, character printing circuit 15, and timing circuit 17. The system can include a data processor or a digital data communications system. Timing circuit 17 accepts synchronizing signals from system 13 and keyboard circuit 11 and generates time base reference signals for activating other circuits. Paper control 19 is a circuit activated by timing circuit 17 and performs the paper start, stop, and rate of paper advance functions. Character-printing circuit 15 is fed by system 13 and keyboard circuit 11 to provide data input while timing circuit 17 provides the time base gating signals.

Character printing circuit 15 converts the binary data input into a character printing dot matrix code and generates high voltage printing pulses.

As shown in FIG. 2, the character printing circuit has inputs consisting of binary coded character data from the system or keyboard, timing pulses from the timing circuit (one pulse per character) and backspace pulses from the keyboard circuit (one pulse for each typist error). Character recognition circuit 101 receives and recognizes each specific binary coded character. Gray counter 103 which is a counter capable of counting either forward or backward, resets character recognition circuit 101 after each character is recognized and printed. Each character recognized presents an activated signal to dot matrix generator 105 which utilizes diodes to channel the received signal to the appropriate points or dots in the matrix for each character-printing configuration. Dot matrix generator 105 provides gating signals to the appropriate dot print gates 107 which isolate the high-voltage print pulse from dot matrix generator 105. The output of dot print gates 107 appear on fixed line matrix array 109 which contains multiple character arrays of 4×6, 5×7, or any other rectangular array.

Gray counter 103, an up-down counter, counts the time pulses received and applies outputs to count recognition gates 111. Gray counter 103 also counts down upon receipt of a backspace pulse from the keyboard, which is received only if a typing error occurs and the typist desired to correct it. Count recognition gates 111 recognize the count in Gray counter 103 and activate the appropriate high voltage pulse gates of circuit 113, which is a circuit that is sequentially gated by the count in Gray counter 103 through count recognition gates 111. When gated, the output is a high voltage pulse (such as between 400 and 600 volts) to character platen 115.

Character platen 115 is aligned with fixed line matrix array 109 and the appropriate character from the line array is printed on electrosensitive paper 117 which passes therebetween.

As shown in FIGS. 3a and 3b, the character printing circuit requires binary coded characters and timing pulse input signals for operation where each character from the keyboard or system is coded to activate, as shown in this example, six bistable multivibrators 121 having six pairs of outputs and producing 2^6 or 64 binary characters. Initially the multivibrators are in the reset state. These six pairs of outputs are fed to character recognition circuit 101 which comprises 64 AND gates. The 64 outputs from character recognition circuit 101 are fed to dot matrix generator 105 which produces 24 outputs to be formed into a 4×6 matrix. If a 5×7 or X×Y array is desired, then there would be 35 or XY outputs, respectively. The 24 outputs are fed to dot print gates 107 which gate the

necessary high voltage from high voltage source 108. Silicon-controlled rectifiers can be used for the gates. The high voltage outputs are fed to fixed line matrix array 109 which is a series of 4×6 arrays. Each high voltage output is fed in parallel to the same dot position in each of 64 arrays on fixed line matrix array 109. While high voltage appears in the same character pattern on all of the 64 arrays on fixed line matrix array 109, the only characters to be printed are those in alignment with an activated segment of character platen 115 which is made of conducting material but is divided into 64 segments by insulators 117. The segments are sequentially activated by six-stage Gray counter 103 initially with the count of zero and which can count up to 2^6 or 64. The 12 outputs of Gray counter 103 are fed to count recognition circuit 111 which comprises 64 AND gates the outputs of which are fed to 64 high-voltage pulse gates 113 which can be silicon-controlled rectifiers. The gated outputs are in turn connected to the 64 segments of character platen 115. When a segment is activated by a gated high voltage, an arc circuit is completed and an impression is made on electrosensitive paper 119. Paper control 19 activated by timing pulses control the paper start, stop, and rate of advance. Operation of the invention would be possible by not having a voltage impressed upon platen 115. Printing would be achieved by adjusting the voltage to fixed line matrix array 109 high enough to arc through electrosensitive paper 119 with platen 115 at ground potential.

Although the invention has been described with reference to a particular embodiment, it will be understood to those skilled in the art that the invention is capable of a variety of alternative embodiments within the spirit and scope of the appended claims.

I claim:

1. An electroarc character-printing system comprising:
  - a. binary input means;
  - b. means for recognizing characters fed by the binary input means;
  - c. a matrix generator having inputs from the character recognizing means and a plurality of outputs representing characters;
  - d. electrosensitive paper positioned adjacent to the output of the matrix generator;
  - e. terminal means for completing an arc circuit through the paper;
  - f. a voltage source connected to the terminal means;
  - g. a plurality of insulators dividing the terminal means into segments;
  - h. means for selecting a segment for printing; and
  - i. the segment selection means comprising a counter and a plurality of count recognition AND gates fed by the counter for recognizing the count thereof, the outputs of the count recognition gates being fed one each to the plurality of segments for the sequential activation thereof.
2. An electroarc printing system according to claim 1 which further comprises:
  - a. a high voltage source; and
  - b. a plurality of high-voltage gates interposed between the high voltage source and one each of the plurality of segments of the terminal means, the high-voltage gates being activated by one each of the plurality of AND gates.
3. An electroarc printing system according to claim 1 wherein the counter is an up-down counter for backspacing.
